RESETTABLE SWITCH

Harold E. Schleicher, Elmwood, Conn., assignor
to The Arrow-Hart & Hegeman Electric Com-
pany, Hartford, Conn., a corporation of Con-
necticut

Application August 27, 1937, Serial No. 161,319

17 Claims. (Cl. 200—116)

This invention relates to a circuit making and breaking device which is automatically operable for circuit interruption and is resettable.

It is an object of my invention to provide an improved form of circuit interrupting device with few inexpensively manufactured parts and which is positive and accurate in operation. Another object of my invention is to provide an improved form of circuit interrupter which is operable by 10 push buttons. Other objects and advantages of my invention will become apparent as it is described in connection with the accompanying drawings.

In the drawings—

Fig. 1 is a sectional view showing in side elevation the interior parts of a circuit interrupting device embodying the principles of my invention, with the parts in closed-circuit position;

Fig. 2 is a view similar to Figure 1 with the 20 parts in tripped position;

Fig. 3 is a view similar to Figure 1 with the parts in open-circuit or reset position;

Figure 4 is a side elevation view of a circuit breaking device embodying the principles of my 25 invention. In this view the thermal tripping means is partly broken away;

Fig. 5 is a transverse sectional view taken along line 5—5 of Figure 3; and

Fig. 6 is a detail view of certain parts of the device in a position which they take before the resetting operation.

Referring to the drawings, my improved circuit making and breaking device is mounted upon a metal plate 10 which may conveniently be stamped from sheet metal. The mechanism is positioned between a pair of parallel plates 12 and 14 which are secured to the base plate 10 by any convenient means, such as by lugs 13 extending from the lower edges of the plates 12 and 14 through the base plate 10, the lug ends being peened over. The parallel side plates 12 and 14 are secured together adjacent their top edges by a narrow plate 16 which may be parallel to the base plate 10 and provided with spaced apertures 45 or slots 16^a, 16^b within which slide the arms 18 and 20.

The device is operated by a pair of push buttons 22 and 24, the button 22 being pressed when it is desired to close the circuit and the button 24 being pressed when it is desired either to open the circuit or to reset the device. The buttons 22 and 24 may be made of insulating material and be mounted upon the ends of the arms 18 and 20 respectively. The arms 18 and 20 may be stamped from sheet metal and bifurcated at

their upper ends to provide for the ready mounting thereon of the operating buttons. The lower or inner ends of these arms 18 and 20 are pivotally connected by pins 25 and 27 with opposite ends of a link 26 which is pivoted at its mid-point upon a pivot 28 located in the upper central portion of the side plates. Also mounted upon the pivot 28 is an operating cam 30, one-half of which is substantially semi-circular while the other half tapers to a point 30^a. The arm 10 5 18 (and also the arm 20) is preferably supplied in duplicate, the pair of duplicate arms acting as a unit with one member of the pair sliding over the inner face of the plate 12 and the other member of the pair sliding over the inner face 15 of the plate 14. The cam 30 and link 26 may also be supplied in duplicate, the pivot 28 on which they are mounted consisting of short duplicate coaxial pins supported in the plates 12 and 14. 20

For the purpose of operating the cam 30 as the operating buttons are manipulated, a cam operating member having the irregular shape as best illustrated in Figure 6, is pivotally mounted upon the pivot pin 27 at the lower end of the arm 26 between the duplicate links 26. One end of this cam operating member 32 extends beyond the side edges of the parallel plates 12 and 14, as indicated at 321. The other end of the cam operating member is of greater width and is provided with a central recess 322 thus dividing the inner end of the cam operating member into two parts, the upper part having an inclined shoulder 323 for engagement by a pin 34 mounted upon the operating cam 30. The lower part of the 25 inner end of the cam operating member 32 has a point 324 which normally will lie in the axis of the pin 28 upon which the cam 30 is mounted. In order to hold the pin 34 against the shoulder 323 duplicate coil tension springs 36 are provided 30 each with one end hooked around the pin 34 and the other end hooked around the pin 27. These springs lie outside the plates 12 and 14 and engage ends of the pins 27 and 34 which project 40 through slots in said plates. It will now be apparent that on account of the action of these 45 springs and the inclination of the shoulder 323 the cam operating member would slip up or move in a clockwise direction (see Figure 1) were it not for the fact that a latch member 38 is provided having an end portion 381 engaged with the point 324 of the cam operating member when the device is set. The latch member is of irregular shape (as best shown in Fig. 6) and may be stamped from sheet metal and be pivotally 50 55

mounted upon a pin 40 which passes transversely through the side plates 12 and 14 in a position below the pivot of the operating cam. The end 381 of the latch member 38 is of hook shape, as illustrated, while the opposite end is of Y-shape. The branch 382 of the Y extends beyond the side edges of the parallel plates 12 and 14 and has connected therewith one end of a coil tension spring 42 which urges the latch in a clockwise direction. The other end of the coil spring 42 is hooked over a lug 44 struck up out of the base plate 10. The other branch 383 of the Y extends toward the base plate 10 and is engaged with an arm 461 pressed out from the center of a latch tripping member 46 which is pivotally mounted upon a base plate 10.

In order to operate the latch tripping member 46 a thermally responsive device 60 may be provided. A suitable type is illustrated in the patent to Monroe Guett No. 2,025,857. In this type of thermal device a plunger springs out when an overload occurs. The plunger, striking an insulating plate 63 between itself and the latch tripping member, causes the tripping member to move in a clockwise direction and, by reason of the engagement of the latch tripping member with the latch 38, the latch 38 is moved in a counterclockwise direction to disengage its upper end 381 from the point 324 on the cam operating member. The cam operating member is then free to move in a clockwise direction under the influence of the pressure of the pin 34 against the inclined shoulder 323. As soon as the pin 34 is disengaged from the shoulder 323 the pin may move into the recess 322 of the cam operating member (see Fig. 2) and the cam 30 will thus be caused to pivot about the pin 28.

The motion of the cam 30 is translated into motion of the switch contacts by the following means. The carrier 50 on which the movable contacts are mounted is stamped from sheet metal into U-shape with the legs 501, 502 slidable over the outside faces of the plates 12 and 14. An insulating block 51 carrying bridging contacts 53 is mounted on the closed end of the carrier 50 by screws 55 engaging in lugs 503, 504 laterally bent from the edges of the legs 501, 502.

The carrier 50 is permitted rectilinear movement, being guided by pins 59 and the projecting ends of pin 40 abutting the lower and upper edges of the carrier's legs. Also guiding the carrier is a pin 54 extending transversely through the carrier legs and sliding in slots 505 in the side plates 12 and 14 and parallel to the base plate 10.

Pivotedly mounted on pin 54 between the side plates 10 and 12 is one end of a channel shaped actuating member 52 for the contact carrier 50. The side plates 521, 522 of this channel member 52 lie between the planes of the cams 30. At the opposite end from the pin 54 a cam roller 56 is mounted transversely in the actuator's side plates 501, 502. This roller engages the tapering surfaces of the cam point 30P during the movement and in the various positions of the device. An expansion spring 58 having one end 581 engaged with the base plate 10 and the other end 582 pressing against the bottom of the actuator 52 holds the cam roller resiliently in contact with the cam surfaces.

It will now be apparent that when the cam moves from the closed circuit position (see Figure 1) into the open circuit position (see Figure 3) the cam will move in a clockwise direction causing the pin 56 to slide down the left in-

clined surface of the cam against the stress of the spring 58 until the pin 56 comes under the point 30P of the cam, at which time the stress of the spring 58 will cause the pin to slide up the right inclined surface of the cam 30, thus causing the actuator 52 for the contact carrier and the contact carrier 50 to move to the right with a snap motion into the position shown in Figure 3, causing separation of the movable contacts from the fixed contacts (not shown).

In order to cause the circuit opening movement of the cam 30, manually, the button 24 must be depressed thereby causing the link 26 to rock clockwise. The downward movement of the pivot pin 27 will cause pivoting of the cam operating member 32 about its point 324 of engagement with the latch end 381, carrying the shoulder 323 clockwise and allowing the springs 36 to pull the pin 34 and cam 30 in a clockwise direction. The springs 36 must be of sufficient strength to rotate the cam against the frictional resistance of the contact actuating parts 50, 52, 60. The springs 36 thus provide means to indirectly transmit the motion of the manually operated link 26 to the operating cam 30 in circuit opening, in contrast to the direct positive transmission of the motion of the link to the cam by the cam operating member 32, during circuit closing.

The movable contacts may be of conventional form having resilient spring mounting, as illustrated, upon the end of the contact carrier 50. These contacts will engage with conventionally formed fixed contacts in closed circuit position and will disengage the fixed contacts when coming into open circuit position.

In order to reset the device after automatic operation, the reset button 24 must be depressed. This will cause the depression of the arm 20 and its pivot pin 27 and also the cam operating member 32 will be simultaneously carried downwardly until the extension 321 engages the extension 382 of the latch. This engagement will cause a resetting of the parts (including the plunger 62 of the thermal device) putting the point 324 of the cam operating member into engagement with the end portion of the latch member 38 and the pin 34 on the cam 30 into engagement with the shoulder 323 of the cam operating member 32. In order to cause movement of the contacts to closed circuit position from the reset position just described (illustrated in Figure 3) the circuit closing button 22 must be depressed thereby causing pivoting of the link 26 which will carry the cam operating member 32 upwardly together with the pivot pin 27 and the resetting arm 20. In moving to this position the cam operating member 32 will pivot about its point of engagement with the latch 38, which point, it will be remembered, is in the axis of the pin 28 upon which the cam 30 is mounted. This movement will also (by reason of engagement of the shoulder 323 or the pin 324) cause counterclockwise movement of the cam 30. During this counterclockwise movement the pin 56 will move down the right hand inclined face of the cam past the point 32 and will slide up the left hand inclined face of the cam causing movement of the actuator 42 and the contact carrier 50 to the left to engage the movable contacts with the fixed contacts to complete the circuit. The device may now be operated to open the switch manually or it may operate automatically to open the circuit by movement of the plunger and latch tripping member 46 as hereinbefore mentioned.

It is obvious that my circuit interrupting mechanism is not limited to automatic operation by a thermal tripping device but may be operated as well by an electromagnet or other automatic tripping means.

Many variations within the scope of my invention will occur to those skilled in the art. Therefore I do not limit the invention to the specific form of the parts as illustrated and described.

I claim—

1. In a circuit controller, manually movable link means, cam means movable in response to movements of said link means, cam operating means for transmitting movement of said link means to said cam means, latch means maintaining operative relation between said cam means and cam operating means, overload current responsive means for tripping said latch and permitting operation of said cam means independent of said link means, in combination with contact means movable with a snap action, resilient connecting means between said contact means and said cam means for imparting movement to said contact means as said cam means moves.

2. In a circuit controller, manually operable means, movable contact means, operating mechanism for moving said contact means to open and closed positions with a snap, means transmitting the motion of said manually operable means to said operating mechanism, means responsive to overload current acting upon said transmitting means to permit operation of said operating mechanism independent of said manual means on overload.

3. In a circuit controller, manually operable means, movable contact means, operating mechanism for moving said contact means to open and closed positions with a snap, means transmitting the motion of said manually operable means to said operating mechanism, said transmitting means being constructed and arranged to provide a rigid connection between said manually operable means and said operating mechanism when said manually operable means is operated in one direction and a resilient connection when said manually operable means is operated in the other direction, means responsive to overload current acting upon said transmitting means to permit operation of said operating mechanism independent of said manual means on overload.

4. In a circuit controller, manually operable means, movable contact means, operating mechanism for moving said contact means to open and closed positions with a snap, means transmitting the motion of said manually operable means to said operating mechanism, said transmitting means being constructed and arranged to provide for direct positive connection between operating mechanism by said manually operable means when said manually operable means moves in one direction and indirect action when said manually operable means is operated in the other direction, means responsive to overload current acting upon said transmitting means to permit operation of said operating mechanism independent of said manual means on overload.

5. In a circuit controller, a reciprocating contact carrier, operating cam means, manually movable means for operating said cam means, actuating means connecting said cam means and contact carrier and causing operation of said carrier with a snap motion, in combination with current responsive mechanism for causing opera-

tion of said cam means independent of said manually movable means.

6. In a circuit controller, a movable contact carrier, operating cam means, actuating means for said carrier mounted on said carrier and resiliently engaging said cam means, manually operable means, means for transmitting the motion of said manually operable means to said cam means, said transmitting means including a member for positively moving said cam means in one direction and a resilient member for causing said cam means to move in the other direction as said manually operable means is moved in one direction or the other, in combination with current-responsive mechanism for causing operation of said cam means by said resilient member independent of said manually operable member.

7. In a circuit controller, movable contact means, operating cam means, means for causing said contact means to move with a snap in response to movement of said cam means, manually operable means, means for transmitting the motion of said manually operable means to said cam means, said transmitting means including a member for positively moving said cam means in one direction and a resilient member for causing said cam means to move in the other direction as said manually operable means is moved in one direction or the other, in combination with current-responsive mechanism for causing operation of said cam means by said resilient member independent of said manually operable member.

8. In a circuit controller, movable contact means, operating cam means, means for causing said contact means to move with a snap in response to movement of said cam means, manually operable means, means for transmitting the motion of said manually operable means to said cam means, said transmitting means including a member for positively moving said cam means in one direction and spring means for moving said cam means in the other direction as said manually operable means is moved in one direction or the other, in combination with current responsive mechanism for disabling said positive moving-member and causing operation of said cam means by said spring member.

9. In a circuit controller, movable contact means, operating cam means, means for causing said contact means to move with a snap in response to movement of said cam means, manually operable means, means for transmitting the motion of said manually operable means to said cam means, said transmitting means including a member for positively moving said cam means in one direction and spring means for moving said cam means in the other direction as said manually operable means is moved in one direction or the other, in combination with current responsive mechanism for causing operation of said cam means by said spring means to automatically operate said contact means.

10. In a circuit controller, movable contact means, operating cam means, means for causing said contact means to move with a snap in response to movement of said cam means, manually operable means, means for transmitting the motion of said manually operable means to said cam means, said transmitting means including a member for positively moving said cam means in one direction and spring means for moving said cam means in the other direction as said manually operable means is moved in one direc-

- tion or the other, in combination with latching means for holding said positive moving means in operative condition, and current responsive means for tripping said latching means and enabling said spring means to operate said cam means to cause automatic operation of said contact means.
11. In a circuit controller, movable contact means, operating cam means, means for causing said contact means to move with a snap in response to movement of said cam means, pivotally mounted manually operable means, means for transmitting the motion of said manually operable means to said cam means, said transmitting means including a member movable with said manually operable means and pivoting about the pivotal axis of said manually operable means during manual operation of the controller, said transmitting means also including spring means for causing said cam means to move in one direction in combination with current responsive mechanism for causing operation of said cam means by said spring means for automatic operation of the controller.
12. In a circuit controller, movable contact means, operating cam means, means for causing said contact means to move with a snap in response to movement of said cam means, pivotally mounted manually operable means, means for transmitting the motion of said manually operable means to said cam means, said transmitting means including a member movable with said manually operable means and pivoting about the pivotal axis of said manually operable means during manual operation of the controller, said transmitting means also including spring means for causing said cam means to move in one direction, in combination with current responsive mechanism for disabling said member movable with said manual means, to permit movement of said cam means by said spring means independent of said manual means for automatic operation of the controller.
13. In a circuit controller, movable contact means, actuating means mounted on said contact means, spring biasing means acting on said actuating means and urging said contact means into one or another of two extreme positions, cam means for moving said actuating means, manually operable means for operating said cam means, means transmitting the motion of said manually operable means to said cam means, said transmitting means including a rigid member for moving said cam means in one direction and a tension member for moving said cam means in the other direction, in combination with current responsive mechanism acting to free said rigid member and permit said tension member to automatically operate said controller.
14. In a circuit controller, movable contact means, actuating means mounted on said contact means, spring biasing means acting on said actuating means and urging said contact means into one or another of two extreme positions, cam means for moving said actuating means, manually operable means for operating said cam means, means transmitting the motion of said manually operable means to said cam means, said transmitting means including a rigid member for moving said cam means in one direction and a tension member for moving said cam means in the other direction, in combination with current responsive mechanism acting to free said rigid member and permit said tension member to automatically operate said controller.
15. In a circuit controller, movable contact means, operating cam means, means for causing said contact means to move with a snap in response to movement of said cam means, manually operable means, means for transmitting the motion of said manually operable means to said cam means, said transmitting means including a member for positively moving said cam means in one direction and a resilient member for causing said cam means to move in the other direction as said manually operable means is moved in one direction or the other, in combination with current-responsive mechanism for causing operation of said cam means by said resilient member independent of said manually operable member, said manually operable means causing resetting of the controller upon movement to another position of rest after automatic operation of the controller.
16. In a circuit controller, manually operable means, movable contact means, operating mechanism for moving said contact means with a snap, means transmitting the motion of said manually operable means to said operating mechanism, said transmitting means being constructed and arranged to provide for direct positive connection between said operating mechanism and said manually operable means when said manually operable means moves in one direction and a non-rigid positive continuously active connection between said operating mechanism and said manually operable means during the movement of said manually operable means in the other direction, means responsive to overload current acting upon said transmitting means to permit operation of said operating mechanism independent of said manual means on overload.
17. In a circuit controller, manually operable means, movable contact means, operating mechanism for moving said contact means with a snap, means transmitting the motion of said manually operable means to said operating mechanism, said transmitting means being constructed and arranged to provide a rigid connection between said manually operable means and said operating mechanism when said manually operable means is operated in one direction and a resilient connection between said manually operable means and said operating mechanism during the movement of said manually operable means in the other direction, means responsive to overload current acting upon said transmitting means to permit operation of said operating mechanism independent of said manual means on overload.

HAROLD E. SCHLEICHER.
